UNITED STATES PATENT OFFICE

JULIAN A. CAMPBELL, OF LONG BEACH, CALIFORNIA

STILL

Application filed April 18, 1927. Serial No. 184,888.

This invention has to do with devices which are variously known as stills, evaporators, strippers or separators; their general function being the evaporation and separation of lower boiling constituents from a mixture also containing higher boiling constituents. Although the invention is not necessarily limited to a particular application and use, stills or strippers of the character here described are commonly used in evaporating and separating off the light hydrocarbons from a body of absorbing oil of higher boiling point; and the operation of the present invention will therefore be described as applied to that particular usage, however without limitation.

In absorption plants for obtaining gasoline from casing head gas, the operations in general include first absorbing the gasoline vapors from the fixed gas into a heavier absorbing oil which is delivered to the absorption apparatus in "lean" condition and comes out of the absorption apparatus in what is known as "rich" or "fat" condition. The rich absorbing oil with its burden of absorbed gasoline is then passed to a still or stripper, usually being pre-heated before reaching the still, a great deal if not most of the heat for evaporation being added to the oil before its release into the still, and evaporation taking place largely by release of pressure. In these stills it is aimed to maintain temperature and pressure conditions such that all of the desirable absorbed constituents are separated from the absorbing oil, leaving the absorbing oil clean to be used over again in the absorption step. It is difficult, however, to maintain conditions such that while all the absorbed constituents are removed, none of the absorbing oil is at the same time evaporated; and this difficulty has led to the subsequent passage of the vapors through a dephlegmator condenser for the purpose of more nearly stabilizing the product, separating and condensing out any absorbing oil vapors. So far as I am aware these two operations have usually been carried on in separate pieces of apparatus and the condensed absorbing oil from the dephlegmator then returned to the main body

of absorbing oil at some convenient point in the lean oil line.

It is an object of this invention to carry out both the described operations in a single piece of apparatus, with attendant advantages and accomplishments that will be best understood from the following detailed description of a specific and preferred form of apparatus illustrative of the invention, reference for this purpose being had to the accompanying drawings, in which:

Fig. 1 is a diagrammatic vertical central section of my improved apparatus;

Fig. 2 is an enlarged fragmentary central vertical section of the middle portion of the apparatus.

Fig. 3 is a similar section of the upper portion of the apparatus.

Fig. 4 is a similar section of the lower portion of the apparatus.

Fig. 5 is a horizontal section on line 5—5 of Fig. 1;

Fig. 6 is a horizontal section on line 6—6 of Fig. 1 and

Fig. 7 is a horizontal section on line 7—7 of Fig. 1.

First to describe the structure of my improved apparatus; it is preferably in the form of an upright cylinder or tower having an outer shell 10 closed at its top with a suitable cap 11, having in its bottom suitable heating means, as steam heating coils 12, to maintain the desired operating temperatures within the apparatus.

Within the outer shell there is a number of perforated plates or floors, including several reflux plates 15, several oil plates 16 and also several agitation plates 17, the oil plates and agitation plates being assembled in pairs as illustrated. To space these several different plates apart there is an inner shell made up of sections 18, 19, 20, 21, 22 and 23, the lowermost inner shell section 18 resting upon an annular angle iron flange 24 welded to outer shell 10, and the uppermost inner shell section 23 preferably having an angle iron flange 25 resting upon its upper edge. These various inner shell sections and the floors supported and spaced thereby are all held together in superposed assembly relation by a

number of bolt rods 26 which pass through the edges of the several superposed floors and have pipe sleeves 27 resting upon upper flange 25 and held down by nuts 28 at the upper ends of the bolt rods. The bolt rods preferably project originally above the upper end of the shell to facilitate stringing of the several plates and flange 25, and flange 29 of cap 11, over the bolts in assembling the structure, the rods being cut off at the upper end after assembly.

A vertical central standpipe 30 extends through all of the floors, is capped at 31 at its upper end, and has oil outlet slots 32 at a point above the uppermost oil plate 16. Near its lower end there is a feed connection pipe 33 through which the rich oil is fed into the standpipe at a suitable temperature. Surrounding this central standpipe and also acting as spacers between the superimposed plates or floors, I provide spacer tubes 34 as illustrated, the standpipe being provided with collars 35 above and below the floors that are spaced apart by the tubes 34. A reflux oil inlet pipe is provided at 40 and delivers the reflux oil over the uppermost reflux plate 15. Mounted above each reflux plate is one or more froth breaking pans 41, each pan being mounted upon a liquid delivery tube 42 which extends through the corresponding reflux plate to deliver liquid to a point near the plate next below, a liquid sealing cup 43 being provided at the lower end of each tube 42 to prevent passage of gas or vapors upwardly through the tube and also for the purpose of more or less spreading the delivery of oil from each tube over the perforated plate just below. The operation of these reflux plates is substantially that which has been described in my co-pending application Serial Number 79,073 filed January 4, 1926 which matured into Patent 1,643,696 on Sept. 27, 1927; and the froth breaking pans 41 may be either of the specific construction described in that application or they may be like the one described in my co-pending application entitled Collector pans for absorbers, Serial Number 184,867, filed April 19, 1927. The operation at each of the reflux plates is one that involves the formation of a mass of froth over each reflux plate, by virtue of vapors passing up through the perforated plates and frothing the liquid which is delivered above the several plates, the body of froth rising to the level of the upper edges of the pan and the froth being broken up at those pan edges, which are preferably sharp, with the result that the freed oil flows over the pan edges into the pans and then down through tubes 42 to be delivered to the floor or plate next below, where the operation is repeated. This operation puts the vapors and liquids into most intimate contact and repeatedly so, and as a result the vapors and liquids reach a

condition of equilibrium, at the temperatures and pressures of operation. The final vapor flows off through the vapor outlet 50 and the remaining liquid proceeds on downwardly to and through the lower perforated plates.

At each of the upper plates at which the reflux liquid is being handled, the operations are characterized by having to do with a comparatively large amount of vapor and relatively small amount of liquid; and therefore the froth breaking pans may be relatively small and occupy a relatively smaller proportion of the total cross-sectional area of the tower. However, the operations in the lower parts of the apparatus characteristically involve a proportionately larger amount of liquid and relatively smaller amount of vapor, and therefore the froth breaking pans above the several oil floors or plates in the lower part of the apparatus are made comparatively large, with a comparatively long froth breaking edge, and occupy a comparatively large proportion of the total cross-sectional area of the tower. This difference in relative areas covered by the pans, and the corresponding differences in froth breaking capacity, may be attained in several different manners. For instance in my application Serial Number 184,867 filed April 19, 1927, mentioned above I show one improved arrangement for obtaining relatively large froth breaking capacity without the necessity of correspondingly increasing the total area occupied by the froth breaking pans; and such an arrangement as there described may be used in this device if desired. However, because in the particular operations of my still, the lower sections are handling comparatively a large amount of liquid and a relatively small amount of vapor, the pan construction for the lower sections may be effectively made as I shall now describe; the presence of a relatively large amount of liquid making it desirable that the pans shall not only have a large froth breaking capacity, but that the pans themselves shall be large, and the presence of a relatively small amount of vapor at that point making it unnecessary to leave uncovered any large proportion of the upper surface area of the froth body.

Consequently as a preferred construction for this still I provide above each oil plate 16 a single pan 55 of the shape and construction shown in detail in Fig. 5. Each of these pans is of an exterior diameter somewhat smaller than the diameter of the inner shell of the tower, the pan having an exterior rim 56 which preferably has a sharp upper froth breaking edge. Within each pan there are several openings 57 of fairly large size each surrounded by a rim 58, also preferably sharp at its upper edge for froth breaking purposes. Each of these pans also has in its bottom sev-

eral openings 59 formed with depending nipples which project into the upper ends of oil delivery tubes 60. These oil delivery tubes form the supports for the several pans and extend through the oil and agitation plate immediately below and on down to and through the next perforated oil plate 16, ending above an unperforated area of the next agitation plate 17 below, all as is best shown in Figs. 1 and 2. These tubes 60 are formed with shoulders, as illustrated in Fig. 2, so that they form spacers between the adjacent plates; and these tubes also pass through the large openings 57 of the pan next below. The lowermost oil delivery tubes 60^a have liquid seal cups 61 at their lower ends to prevent passage of gas directly up through the tubes and they deliver the liquid finally into the lower end of the apparatus directly above the steam heating coils 12, the liquid finding its final outlet at 62 near the bottom of the apparatus but somewhat above the steam heating coils so that a body of oil is at all times maintained over those coils.

The rich oil that is delivered to the apparatus through pipe 33 will, in a typical case, be delivered at a temperature of about 320° F., and under a pressure of 35 lbs. per square inch; this oil being delivered through the slots 32 in standpipe 30 directly over the uppermost oil plate 16 and over the uppermost pan 55. The oil is spread outwardly under pressure, the operating pressure within the apparatus being substantially lower than that at which the oil is delivered (a typical operating pressure in the apparatus is about 30 lbs. per square inch). Oil is thus distributed over the uppermost oil plate 16 as well as over the uppermost pan 55. Whatever oil is delivered directly into this uppermost pan merely flows down through its tubes 60 to the plate next below there to be frothed; and the oil that is delivered onto the uppermost oil plate 16 is frothed by the upwardly moving vapors. A typical froth forming operation takes place at the next set of plates 16, and 17 below. Here the clear oil is delivered between the two plates 16 and 17 spreading out over the perforated agitation plate 17 and being agitated by the upwardly flowing vapors, and then the vapors and oil together pass upwardly through the perforated oil plate 16 more or less in the form of froth, and, in passing through the perforations of plate 16, a mass of froth containing bubbles of fairly uniform size is formed. This mass of froth builds up over plate 16 until the mass reaches the level of the pan just above, the froth is broken up at the several edges of the pan, the clear oil flowing over into the pan and then down through the tubes 60 to the plates next below, the vapors being released to pass on upwardly through the perforated plates next above. This operation is repeated for each set of perforated plates, the liquid being frothed and

refrothed, the gas passing continuously upwardly and the oil passing continuously downwardly through the apparatus until the vapors are finally released from the froth formed with the absorbing oil and pass on up into the reflux operations, and the clear absorbing oil released of its burden finally finding its outlet at the bottom of the apparatus.

In order to increase the agitation within the apparatus steam may be admitted as at an inlet 65 below the lowermost plates, this steam passing upwardly with the vapors and increasing agitation. In a typical operation this steam may be admitted at about 280° F., and as the temperature at the final vapor outlet 50 will typically be about 300° F. the steam will be taken off in vapor form and pass out with the vapors rather than passing out as water with the clean oil.

As I have said, my apparatus is not restricted to any particular use, and although if used for stripping rich absorbing oil it is not necessarily limited to operation at the temperatures and pressures noted. I find it convenient merely for purposes of description to state such temperatures and pressures so that the operation may be well understood. Using such temperatures and pressures thus as a basis of description I shall now proceed to describe how the device as a whole operates under typical conditions. The rich oil, as I have said, is introduced at a temperature of about 320° F.; and the steam coil or other heating means at 12 is operated so that the lean oil leaves the apparatus at about 310° F. The admission of agitating steam at 65 at its temperature of about 280° F. also has a bearing upon the operating temperature maintained in the lower part of the apparatus. But from what I have said it will be seen that throughout the lower part of the apparatus a fairly uniform temperature is maintained on the absorption oil, that temperature ranging only slightly, as between 310 and 320° F. The reflux oil is introduced at 40 at a temperature of about 200° F., and as the temperature of final vapor take-off is typically 300° F., the temperature of operation in the upper portion of the device ranges between those two figures.

It will be understood, of course, that in order to force the vapors up through the successive plates there must be a fall of pressure as the vapors pass upwardly through the plates and that generally speaking the pressures in the sections between lower plates are higher than the pressures between sections of upper plates. The highest pressures maintained in the device, in sections between lower plates, is therefore determined by the temperatures employed, by the nature of the volatile constituents (their vapor tension, etc.) and by the pressure maintained at the final vapor take-off 50. With any given pressure

at the final vapor take-off 50 (in this typical instance that pressure is about 10-15 lbs. per square inch), and other conditions being fixed, the pressure in the space into which the oil is initially discharged through slots 32 will be determined and fixed. That pressure may typically be about 30 lbs. per square inch. At the pressure and temperature thus maintained at the oil discharge at 32 a certain portion of the lighter constituents will be evaporated there; but evaporation from the absorbing oil continues as the absorbing oil passes on down through the plates below, final evaporation of all the lighter constituents being accomplished by the time the oil is ready for final delivery into the lower part of the shell. Consequently as the oil passes down through the lower plates vapors are constantly released which, under the pressures maintained by vapor generation, pass upwardly through the plates to froth the oil as before described. Under the maintained temperatures and pressures these vapors and the absorbing oil tend to come to a condition of equilibrium; so that all of the vapors of lighter absorbed constituents are released to pass upwardly through the tower while the whole body of free absorbing oil, cleared of its absorbed lighter constituents, finally passes off at the bottom. However in order to maintain temperature and pressure conditions that will cause a full evaporation and separation of the lighter absorbed constituents it is almost inevitable that the absorbing oil itself will have a sufficient vapor tension that it is vaporized to some small extent, and a small part of this vapor thus tends finally to pass upwardly from above the uppermost oil plate 16 into the reflux part of the apparatus. Here the whole admixture of vapors comes into frothing contact with the reflux oil, this reflux oil preferably being the oil which is being finally made, in this particular case the gasoline that is finally produced. This gasoline flowing down through the reflux plates as a reflux liquid, and at the temperature and pressure ranges noted, tends to absorb and take up the vapors of the heavier absorbing oil and carry that absorbing oil down with it. At the same time this reflux oil is being evaporated by being raised in temperature within the apparatus, the final vapor take-off temperature being high enough to evaporate off all desirable constituents of the reflux oil, leaving substantially only the heaviest constituents of that reflux oil, and the absorbed oil that came from below, to finally be delivered from the reflux plates down into the absorption oil which is flowing through the lower plates. The constituents of the reflux oil which are thus delivered to the lower parts of the apparatus will thus include some heavier and undesirable portions of the reflux oil, some of the absorbing oil itself, and also perhaps some

lighter portions of the reflux oil which have not been fully evaporated in the upper parts of the apparatus, those constituents all passing down into the reflux oil in the lower part of the absorber. Here, passing into a somewhat higher temperature, they are further evaporated; and during their evaporation are intermittently commingled and contacted with the vapors of the lighter desirable constituents, with the result that all the desirable constituents initially present in or carried down by the reflux oil are re-evaporated; while only the heavy constituents which should finally come out with the absorption oil are not evaporated.

From what I have said it will be seen that my apparatus combines in a single operation and in a single device both the operation of vaporizing and separating the lighter constituents from the absorbing oil and also the operation of refluxing those vapors with a reflux oil. The advantages of carrying these two operations out in a single procedure and in a single piece of apparatus lie largely in simplicity of operation as well as simplicity of apparatus, and further peculiarly in the uniformity of operations and uniformity of results. Further I may speak of the convenience and simplicity of the direct delivery of the unvaporized remnants of the refluxed oil, together with whatever constituents it has absorbed from the vapors, directly into the body of absorption oil which is going through its evaporation process. The final result of the complete operation of the apparatus is a production of a very clean vapor product, substantially wholly clear of any of the undesirable heavy constituents, and the delivery of the absorption oil also in clean condition unmixed with any of its previously absorbed lighter constituents.

I claim:

1. Fractionating apparatus, comprising a vertical shell, a vertical central standpipe extending through the length of the shell and closed at its upper end, liquid delivery openings in the standpipe at an intermediate level adapted to deliver liquid into an intermediate part of the shell, a series of perforated horizontal plates vertically spaced in the shell below said intermediate part, said plates surrounding the standpipe, froth-breaking pans arranged above said plates, liquid delivery tubes extending down from the froth-breaking pans to deliver liquid from them to points above plates below, a series of horizontal perforated plates vertically spaced in the shell above said intermediate part and surrounding the vertical standpipe, froth breaking pans located above said last mentioned plates, liquid delivery tubes extending downwardly from said pans through the corresponding plates to deliver liquid above the plates next below, the liquid delivery tube of the lowermost one of said last men-

80

tioned pans delivering liquid directly into said intermediate part of the shell, and means to introduce a reflux liquid above the uppermost one of said last mentioned plates.

2. Fractionating apparatus, comprising a vertical shell, a vertical central standpipe extending through the length of the shell and closed at its upper end, liquid delivery openings in the standpipe at an intermediate level adapted to deliver liquid into an intermediate part of the shell, a series of perforated horizontal plates vertically spaced in the shell below said intermediate part, said plates surrounding the standpipe, froth-breaking pans arranged above said plates, liquid delivery tubes extending down from the froth-breaking pans to deliver liquid from them to points above plates below, a series of horizontal perforated plates vertically spaced in the shell above said intermediate part and surrounding the vertical standpipe, froth breaking pans located above said last mentioned plates, liquid delivery tubes extending downwardly from said pans through the corresponding plates to deliver liquid above the plates next below, the liquid delivery tube of the lowermost one of said last mentioned pans delivering liquid directly into said intermediate part of the shell, and means to introduce a reflux liquid above the uppermost one of said last mentioned plates, said first mentioned pans being relatively large in horizontal extent and occupying a relatively large portion of the horizontal sectional area of the shell, and said last mentioned pans being relatively smaller and occupying a relatively smaller portion of the horizontal sectional area of the shell.

3. Fractionating apparatus, comprising a vertical shell, means to introduce liquid to be vaporized at an intermediate level in the shell, a series of perforated horizontal plates vertically spaced in the shell below said intermediate level, froth breaking pans arranged above the several plates, liquid delivery tubes extending down from the froth breaking pans to deliver liquid to points above plates below, a series of horizontal perforated plates vertically spaced in the shell above said intermediate level, froth breaking pans located above said last mentioned plates, liquid delivery tubes extending down from the froth breaking pans to deliver liquid over plates below, the liquid delivery tube of the lowermost one of said last mentioned pans delivering liquid directly into the intermediate part of the shell and above the uppermost one of the first mentioned plates, and means to introduce a reflux liquid over the uppermost one of said last mentioned plates, said first mentioned pans being relatively large in horizontal extent and occupying a relatively large portion of the horizontal sectional area of the shell, and said last mentioned pans being relatively smaller

and occupying a relatively smaller portion of the horizontal sectional area of the shell.

4. In a device of the character described, the combination of a shell, a series of horizontal perforated plates vertically spaced in the shell, froth breaking pans arranged above the plates, said pans comprising each a bottom and a peripheral raised rim with a sharp froth breaking edge, the bottom having a plurality of openings therethrough and with peripheral raised rims around said openings, said rims having sharp froth breaking edges, and liquid delivery tubes extending downwardly from the bottom of each pan through the plate below and through the openings in the pan next below to deliver liquid above a plate below the last mentioned pan.

5. A froth breaking device, comprising a flat bottom pan with a raised peripheral rim having a sharp froth-breaking edge, openings through the bottom of the pan provided with peripheral rims with sharp froth breaking edges, and liquid outlets in the bottom of the pan.

In witness that I claim the foregoing I have hereunto subscribed my name this 29th day of March, 1927.
